UNITED STATES PATENT OFFICE.

FRANK A. KATELEY, OF MOUNT VERNON, NEW YORK.

DAMPER-CONTROLLING DEVICE.

1,082,338.

Specification of Letters Patent. Patented Dec. 23, 1913.

Application filed January 9, 1913. Serial No. 740,994.

To all whom it may concern:

Be it known that I, FRANK A. KATELEY, a citizen of the United States, and a resident of Mount Vernon, in the county of 5 Westchester and State of New York, have invented a new and Improved Damper-Controlling Device, of which the following is a full, clear, and exact description.

The invention relates to steam-heating apparatus, and its object is to provide a new and improved damper-controlling device arranged to actuate the damper according to the pressure of the steam generated in the steam-heating apparatus, to prevent 10 spilling of the water in case of excess pressure in the steam-heating apparatus, or in case a siphoning action takes place on forming a vacuum in the steam compartment of the steam-heating apparatus.

For the purpose mentioned, use is made 20 of a pressure tank connected with a source of steam supply and with an expansion tank, a float in the expansion tank and connected with the damper to be controlled, 25 and means governed by said float for closing the expansion tank at the top and at the time the float is in normal lowermost position or in uppermost raised position.

A practical embodiment of the invention 30 is represented in the accompanying drawings forming a part of this specification, in which similar characters of reference indicate corresponding parts in both views.

Figure 1 is a sectional side elevation of 35 the damper-controlling device; and Fig. 2 is a plan view of the float.

Within an expansion tank A is arranged 40 a float B provided with an upwardly-extending stem C connected with one end of a lever D fulcrumed on a suitable support E attached to the expansion tank A. The free end of the lever D is connected by a chain, cable or other flexible connection F with the furnace damper G to be controlled, the 45 damper forming part of the steam heating apparatus. The end of the lever D connected with the stem C is also connected with a chain, cable or other flexible connection F' connected with the flue damper G' of the steam-heating apparatus, so that both 50 dampers G and G' are simultaneously actuated whenever a swinging motion is given to the lever D on the rising and falling of the float B.

The bottom of the expansion tank A is 55 connected by a pipe H with the lower end

of a closed pressure tank I connected at its upper end by a pipe J with the steam compartment of the heating apparatus, so that steam can pass by way of the pipe J into the tank I to condense therein and to exert a pressure on the water contained in the tank I and in the tank A, it being understood that the water level in both tanks I and A is normally at the pipe J so that surplus water can flow by way of the pipe J back into the steam-heating apparatus. When the water in the tanks A and I is at normal level the float B is in lowermost position and the dampers G and G' are both 60 open to insure a proper draft for the generation of steam. The pressure of the steam generated in the steam-heating apparatus produces a pressure on the top of the water contained in the pressure tank I so that the 65 water is forced up in the tank A to cause the float B to rise, and in doing so it actuates the lever D whereby the dampers G and G' are moved into more or less closed position to shut off the draft and to reduce 70 the generation of the steam in the steam-heating apparatus with a view to reduce the pressure of the same. When this takes place the water in the tank A falls and rises in the tank I so that the float B descends to open 75 the dampers G and G' more or less.

The tank A is closed at the top by a cover A' provided with an upper valve seat A² and an under or lower valve seat A³, the seats A² and A³ being in register and 80 through the same passes the stem C of the float B. On the valve stem C is secured a valve K seated on the upper valve seat A² at the time the float B is in lowermost position, as plainly indicated in Fig. 1, so 85 that the tank A is closed during the time the float B is in lowermost position. On the top of the float B is arranged a valve L adapted to be seated on the under valve seat A³ at the time the float B moves into 90 uppermost position, so that the tank A is closed during this time and consequently the water contained in the tank A cannot 95 pass out of the same at the top owing to the closing of the tank A by the valve L seated on the seat A³.

It will be noticed that by the arrangement described the upward movement of the float B is limited by the valve L moving onto the seat A³ and at the same time the expansion 100 tank A is closed to prevent the water contained therein from being forced out of the 105

same and spilled by the excess of pressure on the water in the pressure tank I. When the float B is in lowermost position the tank B is closed by the valve K being seated on the upper seat A², so that in case any vacuum is formed in the upper end of the pressure tank I then the water cannot siphon out of the pressure tank I and the expansion tank A. It is understood that as the water cannot be siphoned out of the tanks A and I there is no danger of cold air passing by way of the tank A, pipe H, tank I and pipe J into the steam chamber of the boiler to the detriment thereof. It is also understood that, when the float B rises, the valve K moves off the seat A² to allow the air in the upper portion of the tank A to escape through the registering and now open valve seats A² and A³. In a like manner, when the float B descends, air can pass through the registering valve seats into the tank A. It will further be noticed that in case of a high steam pressure in the boiler and consequently in the tank I the water in the device cannot be forced out of the same and hence there is no danger of forming an open passage from the boiler to the atmosphere for the steam to escape from the boiler, eventually exhausting all the water in the system.

The lever D is provided with a row of apertures D' any one of which is adapted to be engaged by a pivot pin D² engaging one of a row of apertures E' formed in an upright E² fulcrumed on a bracket E³ attached to the expansion tank A. One of the apertures E' is engaged by a pin E⁴ engaging one of a series of apertures E⁵ held on an arm E⁶ forming part of the bracket E³. By the arrangement described the lever D can be shifted in the upright E² to give more or less throw to the dampers G and G', and the lever D may be raised or lowered on the upright E² to set the lever accurately relative to the stem C and the float B. In a like manner a sidewise adjustment of the upright E² is had on the arm E⁶ to suit existing condition.

Although the damper-controlling device has been described in conjunction with a steam-heating apparatus, it is evident the device can be used for hot water boilers, hot air furnaces and similar heating apparatus.

Having thus described my invention, I claim as new and desire to secure by Letters Patent:

1. A damper-controlling device, comprising a pressure tank connected at its upper end with a source of steam supply, an expansion tank provided with a cover having registering upper and lower valve seats, a connection between the lower ends of the said tanks, a float in the said expansion tank and provided with a valve stem extending through the said seats, valves moving with the said float and its stem, one of the valves being inside of the said expansion tank and being adapted to be seated on the said lower valve seat and the other valve being outside of the expansion tank and being adapted to be seated on the said upper valve seat, a lever connected with the upper end of the said stem, a flexible connection for connecting the lever with the damper to be controlled, and an adjustable support mounted on the expansion tank and on which the said lever is adjustably fulcrumed.

2. A damper controlling device comprising a pressure tank connected with a source of steam supply, an expansion tank, a connection between the lower ends of the said tanks, a float in the expansion tank having an upwardly and exteriorly extending stem, a lever connected with the upper end of the said stem and having a longitudinal series of apertures, an upright arm having an upper longitudinal series of apertures, a bracket to which the lower end of said arm is fulcrumed, a rigid horizontal arm having a longitudinal series of apertures, pivot pins for engagement through selected apertures whereby to adjustably connect the lever and the upright arm, and the upright arm and horizontal arm and flexible connections between the lever and the dampers to be controlled.

In testimony whereof I have signed my name to this specification in the presence of two subscribing witnesses.

FRANK A. KATELEY.
